UNITED STATES PATENT OFFICE

2,138,225

HAT STRUCTURE

Carl Richard Borkland, Boston, Mass.

Application July 3, 1935, Serial No. 29,725

7 Claims. (Cl. 2—181)

The present invention relates to improvements in hat structures and more particularly relates to a harness for supporting the hat upon the head of the wearer.

5 An object of the invention is to provide an improved hat support which eliminates the sweat band now commonly employed and permits ventilation from below to the inside of the hat without use of holes or interstices of the hat.

10 Another object of the invention is to provide an arrangement of hat harness of such a simple nature as to permit of the sale of the harness independently of the hat and its subsequent ready assembly upon the hat by the seller or wearer.

15 A further object of the invention is to provide an improved hat construction which will permit the close nesting of hats to facilitate shipping, it being understood that the hats are, or may be, supported without the elastic harness being 20 fastened thereto and therefore the crown of one hat can be packed within that of another without the harness preventing.

25 A still further object of the invention is to provide an elastic head supporting harness which will permit adjustment by wearer to any size by pulling the harness tight or loose.

With the foregoing and other objects in view, the invention will be more fully described hereinafter, and will be more particularly pointed 30 out in the claims appended hereto.

In the drawing, wherein like symbols refer to like or corresponding parts throughout the several views,

35 Figure 1 is a perspective view of a hat showing the improved harness as applied thereto.

Figure 2 is a side view of the hat, with parts broken away and parts shown in section and illustrating the application of the hat to a human head indicated in dotted lines.

40 Figure 3 is a fragmentary sectional view showing the method of applying one form of fastening.

Figures 4, 5, 6 and 7 are similar views showing modified forms of fastenings, and

45 Figure 8 is a horizontal section taken through the crown of the hat and showing a further method of mounting the elastic tape.

Referring more particularly to the drawing, the hat harness is applicable to any type of hat, but in the drawing there is illustrated a light-weight fibre helmet type of hat constructed with a crown 10 and a brim 11.

According to one form of the invention the crown is provided with slits or openings 12 for receiving therethrough the eye shanks 13 of button eyes 14. Preferably four such button eyes

are employed, two at the front portion of the crown of the hat and two at the rear and the eyes 13 will lie within the crown 10 of the hat while the buttons 14 will prevent the eyes from being pulled inwardly, such buttons 14 being wider than the openings or slits 12. Strung through the eyes 13 is a thin light elastic tape, the ends of which are brought together and tied as indicated at 15 after the tape has been passed through all of the four eyes 13 to provide a rectangular form 10 of head harness or support in which longitudinal side members 16 and 17, a transverse front member 18 and a transverse rear member 19 are component parts. The band slips loosely at all four anchorage points through the eyes 13 so that strain upon one member of the band may be communicated through the eye to the remainder of the band. The harness thus provided is very light and thin having only four points of suspension and presenting a rectangular construction 20 within the crown of the hat.

The elastic relatively long runs of the tape between adjacent anchorage points subtend very wide arcs in the circumference of the brim whereby ample space is left between the tapes and the arcs for the purpose of adequate ventilation

25 and of allowing the head ample space to expand the tapes radially outward in the act of fitting the hat to the head so that the matter of applying the hat to the head is a very easy 30 operation. The conformation of the harness to the head is easy and accurate owing to the light, thin and elastic nature of the harness band.

The suspension is easy on the head and creates a sensation of light-weight which would be impossible with the sweat band type lying against the inside of the brim and fitting close to the head all around. The ventilation is very sure 35 in this type of hat and there is no pressure of the hat upon the head such as might cause baldness.

The invention eliminates head sizes in hats and it also eliminates sweat bands. The hats may be all of the same size and will automatically conform to either large or small heads; or the slits 12 may be punched at advantageous 45 points for various heads, such for instance for narrow heads, the front and rear pairs of slits 12 could be set closer together whereby to bring the tape runs 16 and 17 nearer one another. In other cases such slits could be set further apart 50 so as to cause the tape runs 16 and 17 to be more remote.

Various other fastening devices may be used to hold the tapes in place. In Figure 4 a fastener 20, such as a paper fas-

tener, is employed, which fastener is inserted from the inside through the tape and its ends bent over the outside of the crown of the hat.

In Figure 5 a hook type of device is used, the intermediate portion 21 of the hook passing through an opening in the hat while the inner clamp 22 of the hook may be turned down, as shown in full lines, to clamp the tape, or if it is desired to have the tape in a higher position the clamp member 22 may be turned up as shown in dotted lines. Similarly the outer clamp member 23 may be turned down as shown in full lines or up as shown in dotted lines.

As shown in Figure 6 a staple 24 may be used for clamping the tape upon the inside of the crown, the outer ends of the staple after passing through the crown being clinched over upon the outside of such crown.

As shown in Figure 7 a permanent loop 25 of wire or other suitable material may be made to take the place of the button shanks and the tape may be passed freely through such loop.

Or as shown in Figure 8 pairs of holes or eyes 26 and 27 may be made through the crown at the four points, through which to weave the elastic band.

It will be obvious that various changes may be made in the construction, combination and arrangement of parts which could be used without departing from the spirit of my invention and I do not mean to limit the invention to such details except as particularly pointed out in the claims.

Having thus described my invention, what I claim and desire to secure by Letters Patent of the United States is:—

1. In combination with a hat, the crown portion of said hat having slits therein, buttons larger than said slits fitted on the outside of the crown against said slits, anchorage devices on said buttons projecting through said slits into the inner space of the crown of the hat, and an elastic tape engaged in said anchorage devices and having its runs subtending arcs of the circle of the crown of the hat, said runs extending continuously around the circumference of the hat crown, said runs at the anchorage points being spaced away from the inner wall of the brim to avoid moisture being transferred from the tape to the hat crown.
2. In an improved hat structure including a crown and brim, the combination of anchorage devices carried by the crown portion of the hat adjacent the brim and projecting inwardly away from the inner wall of the crown portion, said anchorage devices being four in number, and

the crown portion of the hat having slits therein, buttons larger than said slits fitted on the outside of the crown against said slits, anchorage devices on said buttons projecting through said slits into the inner space of the crown of the hat, and an elastic tape engaged in said anchorage devices and having its runs subtending arcs of the circle of the crown of the hat, said runs extending continuously around the circumference of the hat crown, said runs at the anchorage points being spaced away from the inner wall of the brim to avoid moisture being transferred from the tape to the hat crown.

3. In an improved hat structure including a crown portion of the hat having slits therein, buttons larger than said slits fitted on the outside of the crown against said slits, anchorage devices on said buttons projecting through said slits into the inner space of the crown of the hat, and an elastic tape engaged in said anchorage devices and having its runs subtending arcs of the circle of the crown of the hat, said runs extending continuously around the circumference of the hat crown, said runs at the anchorage points being spaced away from the inner wall of the brim to avoid moisture being transferred from the tape to the hat crown.

located two at the front portion of the hat and two at the rear portion of the hat, and a single length of thin narrow elastic tape strung slidably through the inner portions of said anchorage devices out of contact with all portions of the hat, said tape having its ends secured together, said tape extending in four runs, the front anchorage devices being so positioned as to stretch a single run of the elastic tape across the forehead, the rear anchorage devices so positioned as to stretch a single run of the tape across the rear of the head, said front and rear anchorage devices being so positioned as to stretch single runs of the tape along the sides of the head, said single runs of the tape being of considerable length whereby the head will bulge such runs outwardly without the tape coming in contact with the hat at any point and leaving space between the head and the hat for ventilation.

3. A sweat band device comprising supporting means secured to the hat in spaced relation, a sweat band slidably connected to said supporting means and having free ends so arranged and constructed to be knotted together as desired for any given size of sweat band.

4. A hat, attaching elements connected thereto at wide intervals, a narrow tape slidably attached to said elements and having free ends adapted to be knotted together, said tape when tied forming a geometric figure having sharp corners and adapted to be the only part of the hat contacting the wearer thereof.

5. A sweat band device comprising supporting means secured to the hat in spaced relation, a sweat band slidably connected to said supporting means and having free ends so arranged and constructed to be adjustably connected together as desired for any given size of sweat band.

6. A hat, attaching elements connected thereto at wide intervals, a sweat band slidably attached to said elements and having free ends adapted to be adjustably secured together, said sweat band when secured in place forming a geometric figure having sharp corners and adapted to be the only part of the hat contacting the wearer's head.

7. A hat, attaching elements connected thereto at wide intervals, a hat-supporting band, each of said attaching elements having means for slidably receiving the sweat band, said sweat band being slidably mounted in said means and having free ends, the free ends of the sweat band being adapted to be secured together in any one of numerous different positions as desired for any given size of head.

CARL RICHARD BORKLAND.
